UNITED STATES PATENT OFFICE.

PHILIP REITER, OF NEW YORK, N. Y.

DESIGN FOR A JEWEL-MOUNTING LINK.

51,187.

Specification for Design.

Patented Aug. 21, 1917.

Application filed May 26, 1917. Serial No. 171,327. Term of patent 14 years.

To all whom it may concern:

Be it known that I, PHILIP REITER, a citizen of the United States, residing in New York city, county and State of New York, have invented a new, original, and ornamental Design for a Jewel-Mounting Link, of which the following is a specification, reference being had to the accompanying drawing, forming a part thereof.

The figure is a plan view of a link embodying my invention.

I claim—

The ornamental design for a jewel mounting link as shown.

PHILIP REITER.
